UNITED STATES PATENT OFFICE.

WILLIAM H. KAY, OF LYNN, MASSACHUSETTS.

LAST-ENGAGING DOG FOR LAST LATHES.

Application filed August 31, 1926. Serial No. 132,836.

This invention relates chiefly to last lathes for returning an old last which is of obsolete form, or has been rendered by wear incapable of further use, the size of the last being such that it may be converted into a smaller last by a returning operation performed by a last lathe, the shape or style of the last being at the same time suitably changed.

10 An element of said machine is a last-engaging dog comprising a body adapted to be coupled to the live spindle of the lathe, so that the body is coaxial with the spindle, a spur co-axial with the body and projecting 15 from the outer end thereof, to enter the heel end of a last, and a pair of centering ears fixed to the body and projecting from the outer end thereof, at one side of the spur, and adapted to bear on opposite sides of the 20 heel end of the last, between the top thereof and the spur, the arrangement being such that the median line of the last and its heel end may stand at various inclinations, while the heel end is engaged with the spur and 25 supported laterally by said ears.

A dog thus characterized is shown by my Patent No. 1,493,780, dated May 13, 1924, said dog being provided with a rest adjustable on the body and projecting forward 30 therefrom in position to bear on the heel seat portion of the last bottom, so that the last is supported at one side of the spur by the centering ears, and at the opposite side by the rest.

35 The present invention is an improvement on the dog disclosed by the above-mentioned patent, and has for its object to provide a rigid and compact dog, adapted to engage the last at three points on its heel end, without engaging or bearing on the heel seat portion thereof, so that the last may be adjustably supported, without the liability of displacement which exists when the dog is provided, as heretofore, with a rest projecting 40 from its body sufficiently to bear on the heel seat of the last.

Of the accompanying drawings forming a part of this specification,—

Figure 1 is a view showing partly in plan

and partly in section, portions of a last lathe 50 including two of the improved heel-engaging dogs hereinafter described.

Figure 2 is a top plan view, and

Figure 3 an end view of one of the dogs.

Figure 4 is a section on line 4—4 of Figure 2.

Figure 5 is a side view, showing the dog and a portion of the heel end of a last.

Figure 5 is a fragmentary view similar to a portion of Figure 5, showing a different adjustment.

Figure 6 is a perspective view of the slide, constituting a part of the dog shown by the preceding figures.

Figure 7 is a view similar to Figure 3, 65 showing a modification.

Figure 8 shows in perspective the slide constituting a part of the dog shown by Figure 7.

Figure 9 is a section on line 9—9 of Figure 7.

The same reference characters indicate the same parts in all of the figures.

14 designates a pattern last, and 15 a last which is to be, or has been re-turned by a 75 last lathe, said lasts being mounted in the swinging holder of an ordinary lathe, the pattern last bearing on the pattern wheel 16, and the last 15 being acted on by the rotary-cutter head 17.

80 The heel end of each last is engaged by a dog embodying the invention.

Each dog includes a substantially cylindrical body 18, provided at its outer end with a transverse end face 19, and with last-centering means embodied in a pair of ears 20, projecting from one edge of the end face and having converging edges 21, adapted to bear simultaneously on opposite sides of the heel end portion of a last, so that longitudinal pressure exerted by the usual adjustable dog 22, constituting a part of the loosely rotating or dead spindle of the lathe, centralizes the heel end by forcing it toward the apex of the notch formed by the edges 21.

95 The end face 19 is offset inwardly from said notch to permit various inclinations of the heel end of the last. From the end face

19 projects a fixed spur 24, which is coaxial with the body 18, and is adapted to enter an indentation previously formed for its reception in the heel end of the last.

5 When the last is operatively installed, its toe end is engaged by the loosely rotating dog 22, and its heel end is impaled on the spur 24, and gripped between the ears 20 of the positively rotated dog 18, so that the last 10 is positively rotated, its heel end being positioned in accordance with the location of the indentation entered by the spur 24. The last is automatically centered by the converging edges 21, and its longitudinal inclination is 15 determined by the location of said indentation.

The body 18 of each dog is provided with coupling means, adapted to be interengaged with complementary coupling means on the 20 corresponding live spindle, the coupling means on each body being preferably a socket 26, into which opens a slot 27, said socket and slot conforming to a correspondingly formed terminal on the corresponding live 25 spindle, the arrangement being such that the dog body is coaxial with the live spindle.

The centering ears 20 are preferably integral with the body, are non-adjustable relative thereto, and are located at one side 30 of the spur 24. The body 18 is preferably cylindrical, as shown by Figure 3. The portion of the cylindrical periphery of the body opposite that from which the centering ears 20 project, constitutes a transversely convex seat on which a slide 30 is longitudinally movable, the slide being curved as shown by Figures 3 and 6, so that it has a transversely concave inner face conforming to the convex seat, and having an elongated bearing on the body. The slide is 40 provided with last-centering means embodied in a pair of ears 31, formed on the outer end of the slide by a notch 32, therein, as shown by Figure 6. Said ears project from the body 18 at the opposite side of the spur 24 from the fixed ears 20. The slide is longitudinally adjustable on the body 18, to vary the projection of the ears 31, as shown by Figures 5 and 5^a, Figure 5 showing a minimum, and Figure 5^a a maximum projection of said ears. I provide clamping means engaging the body and the slide, and adapted to confine the slide in any position to which it may be adjusted. In this 55 instance, the clamping means is embodied in a bolt 33, inserted in a socket in the body 18, and provided with a head 34 and a nut 35. The head confines a washer 36 against the slide 30, and the nut confines a washer 37 against the body 18. The inner faces of said washers are preferably curved, as shown by Figure 3. The slide 30 is provided with a slot 38, through which the bolt passes, the slot permitting any desired ad-

justment of the slide. The centering ears 65 31 are so spaced from the spur 24, that they are adapted to bear wholly on a portion of the heel end face L of the last, and not upon the heel-seat face L' thereof.

The arrangement is such that a last may 70 swing on the spur 24, and its heel end face L may be supported by the two pairs of ears 20 and 31, at various inclinations while engaged with the spur, as indicated by Figures 5 and 5^a, the adjustable centering ears 75 31, cooperating with the spur and with the fixed centering ears 20, in engaging the heel end face L of the last at a plurality of points above the heel-seat face L' and positively maintaining the last at various 80 inclinations relative to the spur. The convex slide seat formed by a portion of the periphery of the cylindrical body, and the concave inner face of the slide 30 cooperate in preventing the slide from turning. The 85 slide is therefore prevented from turning on the bolt 33. The major portion of the slide is rigidly backed by the body, so that yielding or springing of the centering ears 31 is prevented, the curvature of the slide 90 imparting rigidity to said ears.

Although I prefer the last described form of the body and slide, I am not limited thereto. The slide may be flat, as shown by Figures 7, 8 and 9, and the body 18 may be 95 provided with a flat face or seat 40 (Figure 7) on which the flat inner face of the slide bears. In this modification the turning of the slide on the bolt 33 is prevented by an ear 41, pressed outward from the slide, and a longitudinal groove 42 in the body 18, in which the ear 41 is slidable.

I claim:

1. A last dog comprising a body having means at one end whereby it may be coupled to the live spindle of a last lathe, so that the body is coaxial with the spindle, and provided at its opposite end with a spur coaxial with the body and formed to engage the midlength portion of the heel-end face of a last, and with fixed non-adjustable centering ears projecting from the body at one side of the spur, and formed to engage the upper end portion of said end face, a slide movable on the body in a direction parallel with the axis thereof, and provided with centering ears projecting from the body at the opposite side of the spur, and spaced therefrom to engage the lower end portion of the heel-end face of the last, and means for releasably clamping the slide to the body, so that the centering ears of the slide may project variably from the body, the arrangement being such that the adjustable centering ears cooperate with the spur and the fixed centering ears in engaging the heel-end face of the last at a plurality of points above the heel-seat face 105 110 115 120 125

thereof, and positively maintaining the last at various inclinations relative to the spur.

2. A last dog as specified by claim 1, the clamping means being embodied in a bolt extending through the body and through a longitudinal slot in the slide and having a clamping head and a clamping nut, the body being provided with a transversely convex

slide seat, and the slide being curved and having a transversely concave inner face contacting with the seat, so that the slide is confined against turning movements on the bolt.

In testimony whereof I have affixed my signature.

WILLIAM H. KAY.
